UNITED STATES PATENT OFFICE.

OTTO B. SCHOENKY, OF SACRAMENTO, CALIFORNIA.

DRILL-HOLDER.

1,101,966.

Specification of Letters Patent. Patented June 30, 1914.

Application filed February 3, 1913. Serial No. 746,022.

To all whom it may concern:

Be it known that I, OTTO B. SCHOENKY, a citizen of the United States, residing at Sacramento, in the county of Sacramento 5 and State of California, have invented a new and useful Improvement in Drill-Holders, of which the following is a specification.

My invention relates to a drill holder, especially applicable to a pneumatic drill, 10 and has for its object to enable the operator to handle and move the drill in any direction when required to change its position for drilling a succession of holes, without the necessity of lifting and using a tool for 15 re-setting the drill as at present, thereby saving time and labor and insuring greater accuracy of work.

It consists in features of novelty as hereinafter described and claimed, reference being had to the accompanying drawing forming 20 part of this specification, whereon,

Figure 1, is a perspective side view of my improved drill holder as applied to a pneumatic drill for drilling a series of holes 25 through a steel casting (represented in the present case as part of a double body-bolster and platform connecting frame for a railroad car); Fig. 2, a side sectional elevation to enlarged scale, of the adjustable 30 arm (broken away) and its appendages forming parts of my improved holder as seen in Fig. 1; Fig. 3, a top plan thereof; Fig. 4, a vertical transverse section through the same on line 4, 4, in Fig. 2; Fig. 5, a 35 vertical longitudinal section to enlarged scale through the locking block forming part of the holder as seen to the left of Figs. 1 and 2; Fig. 6, a top plan of the same; Fig. 7, a similar view to Fig. 2 of the pivoted 40 end portion or hub of the adjustable arm as seen to the left of Fig. 2, detached, and Fig. 8, a section to enlarged scale, through the swivel joint of the drill carrier forming part of the holder.

Like letters and numerals of reference denote like parts in all the figures.

My improved drill holder consists of a preferably, circular upright post *a* which in the present case is affixed at its lower end to 50 a horizontal base piece 1 adapted to bear on the face of the casting *b* to be drilled

and firmly secured thereto by a clamp 2 as shown. Or the post *a* may be otherwise removably fixed to the casting *b* in any suitable manner.

Projecting from the post *a* is a horizontally arranged arm *c* which may be of any suitable length and construction, and is adapted to be vertically adjustable along, and radially about the post *a*. In the present case, the arm *c* is formed at one end with a centrally perforated circular hub or boss 3, which is fitted around and slideable along the post *a*, the hub 3 being formed circumferentially at its lower end with a semi-circular projection having therein a correspondingly shaped recess 3' which is concentric with, and diametrically larger than the post *a*. 4 is a bush or sleeve, which is also slideable along the post *a* and formed at its upper end with a circular collar 4' which is adapted to be inserted within the recess 3', whereby the hub 3 is slideable with the bush 4 along the post *a* and rotatable on the latter independently of the bush 4 which is normally fixed to the post *a* by a set screw 5, as hereinafter more particularly referred to.

From the periphery of the hub 3 project two opposite and preferably, L-shaped 80 brackets 6 of suitable length, having their upright legs parallel to and spaced apart from each other for receiving one end portion of the upright web of a horizontally arranged and preferably, inverted T-shaped 85 bar 7 which may be of any desired length and with the hub 3 constitutes the arm *c* of the holder, the horizontal legs of the brackets 6 bearing on the corresponding end portions of the bottom flanges of the bar 7 90 and the said legs and flanges fixed together by rivets 8, 8', respectively as shown.

To the underside of the bar 7 at its outer free end is fixed a bearing 9, and to the underside of the bar 7 adjacent to the bush 4 95 and hub 3 is fixed a similar bearing 10, the bearings 9 and 10 being perforated longitudinally and parallel to the underside of the bar 7, and in alignment with each other for the passage therethrough of a circular rod 100 or shaft 11 having a handle 12 at its outer end beyond the bearing 9, and having an

enlarged screw-threaded portion of suitable length where it passes through and engages with the correspondingly threaded perforation of the bearing 10, the other or inner 5 end of the rod 11 adjacent to the bush 4 being formed with a circular collar 11' which is inserted and rotatable within a semicircular recess 13 formed vertically in a locking block *d* and opening therefrom through its 10 underside, the outer face *x* of the block *d* being knurled or roughened for engagement with the periphery of the bush 4 as herein-after more particularly referred to.

The carrier *e* for the pneumatic drill *f* 15 which is of the usual well-known construction consists in the present case preferably, of two parts viz: an upper part adapted to be supported by, and to travel along the arm *c*, and a lower part swiveled to the upper part and engaged by the drill *f* as herein-after more particularly described.

The upper part 14 of the carrier *e* is preferably bifurcated and adapted to straddle the base of the bar 7. To the inner face of 25 each branch of the bifurcated portion is pivoted a roller 15 which is adapted circumferentially to bear on and travel along the corresponding bottom flange of the bar 7, the part 14 at the junction of its bifurcation beneath the bar 7 being formed with a central vertically dependent circular shank 14' having a central pocket 16 in, and for a suitable depth from its upper face, and thence formed with a central vertical perforation through the bottom end of the shank 30 14' for receiving a circular bolt 17 having a head 17' which bears on the bottom of the pocket 16, the bolt 17 projecting below the shank 14' and engaging in a pocket formed 35 therefor in, and for a suitable depth from the upper end face of the lower and preferably circular part 18 of the carrier *e*, the bolt 17 being fixed to the part 18 by a pin 40 19, or in any other suitable manner.

45 In the meeting faces, or thereabout, respectively of the parts 14 and 18 are formed preferably square shaped (or circular) grooves 20 which are concentric with the bolt 17, the grooves 20 registering with each 50 other for receiving a series of balls 21, whereby the lower part 18 of the carrier *e* is swiveled to and carried by the upper part 14, and at the same time rotatable at all 55 times independently thereof.

55 In the bottom end face, and for a suitable depth therefrom, of the lower part 18 is formed a vertical circular socket 22 in which is centered, and removably fixed by a set screw 23, the pivotal shaft 24 of the drill 60 *f*, which is thereby dependently held by the carrier *e* ready for use at all times in whatever position the latter is moved.

For holding the carrier *e* to the bar 7 at

any point of its travel along the same, one of the branches of the bifurcation of the 65 upper part 14 is formed with an ear or lug 25 through which is threaded a set screw 26 having a suitable handle 27 within reach of the operator, whereby the free end of the screw 26 can be engaged with the edge of 70 the bar 7. Or any other suitable means may be used for this purpose.

It will be noted that the upper end of the shank 14' of the part 14 beneath the bar 7 and above the head of the bolt 17 is so 75 shaped as to be clear of the rod 11 at all times during the travel of the carrier *e* to and fro along the bar 7.

In operation, assuming the parts of the holder while drilling the hole marked *y* 80 through the casting *b* to be in their normal position as shown in Fig. 1, or in other words with the bush 4 and combined hub 3 of the arm *c* fixed to the post *a* by the set screw 5, and the carrier *e* held to the arm *c* 85 by its set screw 26, and the arm *c* locked and prevented from radial movement about the post *a* by the locking block *d* having its knurled face *x* in frictional contact with the periphery of the bush 4, and it being desired on finishing the hole *y* to move the drill *f* into another position for drilling another hole marked *z* in the casting *b*, by withdrawing the drill bit from the hole *y* by the drill handle 28, and turning the rod 95 11 in one direction, or toward the operator, the locking block *d*, owing to the screwed portion of the rod 11 in its bearing 10, will be released from contact with the bush 4, whereby the arm *c* will be free to be radially 100 moved in the direction of the hole *z* to be drilled and should the movement of the carrier *e* along the bar 7 be necessary for bringing the drill *f* over the mark *z* the carrier *e* can be released and free to be moved along 105 the arm *c* by disengaging its set screw 26 from the bar 7. On the adjustment of the drill *f* over the mark *z* being thus made, the locking block *d* and carrier *e* are returned to their normal position or so as to lock the 110 parts of the holder as before, by reversing the movement of the rod 11 and set screw 26 respectively. Furthermore, if required the arm *c* with the carrier *e* and drill *f* may be raised or lowered along the post *a* by releasing the set screw 5 of the bush 4 from engagement with the post *a*; or in other words, by this invention the drill *f* can be moved in any direction and held in the adjusted position without having to lift and 115 re-adjust it directly by hand and the use of tools as at present, whereby a considerable saving of time and labor is effected.

What I claim as my invention and desire to secure by Letters Patent is:—

A drill holder, consisting of a member

adapted to be fixed at right angles to the face of the object to be drilled, an arm pivoted at right angles to, and slideable along the fixed member, a bush carried by the arm and rotatable on the fixed member independently from the said arm, a carrier for the drill supported by and movable along

the arm, means for fixing the said bush to the fixed member, and means for locking the arm to the said bush.

OTTO B. SCHOENKY.
